UNITED STATES PATENT OFFICE.

ALVA MAY, OF MACEDONIA, IOWA, ASSIGNOR TO THE OLIVER TYPEWRITER COMPANY, OF CHICAGO, ILLINOIS, A CORPORATION OF ILLINOIS.

PRINTING-POINT INDICATOR FOR TYPE-WRITERS.

No. 893,256.

Specification of Letters Patent.

Patented July 14, 1908.

Application filed December 13, 1907. Serial No. 406,345.

To all whom it may concern:

Be it known that I, ALVA MAY, a citizen of the United States, and a resident of Macedonia, in the county of Pottawattamie and State of Iowa, have invented certain new and useful Improvements in Printing-Point Indicators for Type-Writers; and I do hereby declare that the following is a full, clear, and exact description thereof, reference being had to the accompanying drawings, and to the letters of reference marked thereon, which form a part of this specification.

This invention relates to a device for use in typewriting machines for the purpose of indicating to the eye the printing point on the paper, or the point at which the type will strike the paper when the paper-carriage is released from its letter-spacing mechanism and moved by the hand of the operator to a point at which it is desired to begin a line or word, or to insert one or more letters in a line already printed.

The invention is more especially applicable to typewriters of the kind known as the "Oliver" but is adapted for use in other forms of visible writing machines, or those in which the printing point is visible to the operator during the progress of the printing.

The invention consists in the matters hereinafter described and pointed out in the appended claims.

My invention may be more readily understood by reference to the accompanying drawings, in which

Figure 1 is a view in central vertical section showing the platen and the forward portions of a paper-carriage of an "Oliver" typewriting machine equipped with my improvements. Fig. 2 is a plan view of the parts shown in Fig. 1. Fig. 3 is a plan view of the movable indicating member and associated parts. Fig. 4 is a sectional plan view taken on line 4—4 of Fig. 1.

As shown in said drawings, 1 indicates the platen, and 2 the lower, forward, transverse frame bar of the paper-carriage in which the platen is mounted. Said frame-bar 2 is provided at its forward edge with rack-teeth 3.

4 indicates an upright rotative shaft, which forms part of the letter-spacing mechanism of the machine. To the upper end of said shaft 4 is attached a gear pinion 5 which intermeshes with the rack-teeth 3 on the carriage frame-bar 2 and to the lower end of said

shaft is attached an escape-wheel 6, in connection with which operate a pawl 7 and an oscillating escapement lever 8 which is operated by all of the key-levers of the machine. Said shaft 4 is rotated through the action on the pinion 5 of the rack-teeth on the carriage, which latter is given endwise movement by the actuating spring of the machine, and the rotative movement of said shaft is controlled by the letter-spacing mechanism including an escape-wheel 6 and lever 8, as in the "Oliver" typewriter and other typewriting machines having a rack-and-pinion connection between the letter-spacing mechanism of the paper-carriage.

9 indicates the shift-frame of the machine on which the carriage is supported and on which the shaft 4 and associated parts are mounted. Said shift-frame is provided with a supporting arm 10 which rises in front of the lower frame-bar 2. This supporting arm 10 is provided with a transverse guide-slot in which is mounted a bearing block 11 through which passes the upper end of the shaft 4. Said upper end of the shaft 4 with its pinion 5 is movable toward and from the frame-bar 2 by the sliding of the block 11 in said supporting arm, and a coiled spring 12 which is inserted between the said block and the outer end of said slot acts to hold the pinion in mesh with the rack-teeth 3.

13 indicates a carriage release-bar which is mounted on the top of the carriage frame-bar 2 and slides horizontally forwardly and rearwardly thereon. The forward edge of said release-bar is adapted for contact with a rotative ring 14 mounted on the upper end of the shaft 4 above the gear pinion 5. Said release bar is adapted to be moved or shifted forwardly by manually operated devices on the paper-carriage, for the purpose of disconnecting the gear-pinion from the rack-teeth and thereby releasing the paper-carriage from the letter-spacing mechanism, in order to permit free endwise movement of the carriage, under the control of the hand of the operator, as in the "Oliver" typewriter.

15 indicates a rigid supporting standard which is attached to and rises from the arm 10, the same being secured to the right-hand side face of the said arm 10. The standard 15 corresponds with the standard employed in the "Oliver" typewriting machine for supporting the parts constituting the ribbon

throw mechanism. Said ribbon throw mechanism constitutes no part of the present invention and is not, therefore, illustrated in the accompanying drawings.

5 16 indicates a vertically arranged rock-shaft which is pivotally supported on the standard 15 and is provided at its upper end with a horizontally arranged pointer or indicating arm 17 adapted to extend over the top 10 of the platen with its free end adjacent to the printing point, and which is adapted for lateral oscillation in a manner to carry it towards and away from said printing point, through the turning of said rock-shaft. Said 15 indicating arm stands normally at a distance from the printing point, so that it will at such time be out of the way of and will not interfere with the type in making the impression, but is adapted to be swung laterally to a position 20 with its free end or point opposite or in line with the printing point. Attached to the lower end of said rock-shaft 16 is a rigid horizontal arm 18 which extends therefrom toward and in a position to be acted upon by 25 the sliding block 11 in which the upper end of the pinion-shaft 4 has bearing. A spring 19 is applied to said rock-shaft 16 to turn the same in a direction to carry the pointer 17 toward the printing point and to hold the 30 arm 18 on the shaft 16 pressed against the forward or outer face of said block 11.

In the particular construction illustrated, the rock-shaft 16 is located at the rear of the standard 15, and bearings for said rock-shaft 35 are afforded by means of a vertical plate 20 secured to the right-hand face of the standard 15 and which has at its rear edge upper and lower, rearwardly projecting lugs 21 and 22 provided with bearing apertures for said 40 rock-shaft. In this construction the spring 19 is of coiled form and surrounds said shaft between the lugs 21 and 22; said spring being connected at one end with the shaft and at its opposite end with one of said 45 lugs. The swinging movement of the pointer and rock-shaft, under the action of said spring, is limited by the contact of the arm 18 with the sliding block 11; the parts being so arranged that when the said block is at the 50 rearward limit of its movement, the said pointer will stand at the printing point. The pointer will preferably be made of such length that its rear end or point will extend to the lower edge of the printed line and will 55 reach somewhat beyond the inner or rear edge of the scale-bar 25, which is shown as extending along the platen forward of the printing line, as in the said "Oliver" machine. To hold the said rock-shaft from 60 vertical movement in the bearing lug, a collar 23 is applied to the shaft above the lower bearing lug 22, and a pin 24 is inserted through the rock-shaft below said lower bearing lug.

The parts described are so arranged that 65 when the release bar 13 is shifted outwardly

on the carriage and the gear pinion 5 is, by the pressure of said release-bar, on the upper end of the shaft 4, swung outwardly to release said pinion from the rack-teeth 3, the arm 18 on the lower end of the rock-shaft 70 will be thrown outwardly by the action of the block 11 thereon, and the rock-shaft 16 thereby turned or swung in the direction to carry the pointer 17 thereon laterally to the printing point, or to the place at which the impression will be made in the succeeding action of one of the types on the paper. It follows that during the endwise movement of the paper-carriage, effected by the operator in order to bring the paper in the position desired for starting a word or for inserting an erased letter, the pointer 17 will stand exactly opposite and will correctly indicate the printing point on the paper. When, however, the gear pinion is released and allowed to resume its engagement with the rack-teeth on the paper-carriage, the rock-shaft will be turned or swung by its spring 75 so as to carry the pointer 17 away from the printing point and out of the way of the type. 80

In the normal condition of the parts, or when the paper-carriage is under the influence of the letter-spacing mechanism, the pointer will be held away from its indicating position, so that it will not in any way interfere with the strokes of types against the 90 paper in the printing operation. When, however, the paper-carriage is released from the letter-spacing devices and is free to be moved by the hand of the operator, the 95 pointer will indicate the exact point at which the type will strike when the carriage is re-engaged with the letter-spacing device and the printing is proceeded with.

In its broader aspect, my invention includes a printing point indicator movable into and out of its indicating position, and which is moved or shifted, through the action of parts concerned in the connection of the paper-carriage with and its release from the 105 letter-spacing mechanism, in such manner that the pointer of the indicating device will be brought into its indicating position when the paper-carriage is released from said letter-spacing mechanism, and will be moved away 110 from such indicating position when the paper-carriage is connected with the letter-spacing mechanism.

It follows that so far as the broader aspects 115 of my invention are concerned, the pointer may be moved into and out of its indicating position by means other than the particular devices illustrated.

I claim as my invention:

1. In a typewriting machine, the combination 125 with a platen, a paper-carriage, letter-spacing mechanism, and a part which is moved or shifted to disconnect the carriage from said letter-spacing mechanism, of a movable pointer and an operative connection 130

between said pointer and said part which is so moved or shifted to disconnect the paper-carriage from the letter-spacing mechanism.

2. In a typewriting machine, the combination with a platen, a paper-carriage and letter-spacing mechanism embracing rack-teeth on the paper-carriage, and a pinion adapted for engagement with said rack-teeth, said pinion being movable into and out of engagement with said rack-teeth for disconnecting the paper-carriage from said letter-spacing mechanism, a pointer movable toward and from the printing point, and actuating means for the pointer controlled by the movement of the said pinion and operating to effect the shifting of the pointer to the printing point when said pinion is released from the rack-teeth and to throw the pointer away from the printing point when the pinion is engaged with said rack-teeth.

3. In a typewriting machine, the combination with a platen, a paper-carriage provided with rack-teeth and a pinion forming part of the letter-spacing mechanism of the machine and which is movable toward and from the rack-teeth, of a movable pointer, a spring acting on said pointer to throw the same toward the printing point, and means actuated through the movement of the pinion acting

to hold the pointer away from the printing point when said pinion is engaged with said rack-teeth and to permit the said spring to move the pointer to the printing point when the pinion is disengaged from the said rack-teeth.

4. In a typewriting machine, the combination with a platen, a paper-carriage provided with rack-teeth, and letter-spacing mechanism embracing a pinion adapted to intermesh with said rack-teeth and which is movable into and out of engagement with the same, an upright shaft on which said pinion is mounted, and a sliding block affording bearing for the upper end of said shaft, of an upright rock-shaft provided with a horizontally oscillating pointer, and with a rigid arm engaged with said sliding block, and a spring applied to said rock-shaft and acting on the same in a direction to throw the pointer toward the printing point.

In testimony, that I claim the foregoing as my invention I affix my signature in the presence of two witnesses, this 9th day of December A. D. 1907.

ALVA MAY.
